UNITED STATES PATENT OFFICE.

ROBERT C. GROH, OF ST. PAUL, MINNESOTA, ASSIGNOR OF ONE-THIRD TO GEORGE F. GETSEY, OF MINNEAPOLIS, MINNESOTA, AND ONE-THIRD TO FRANK X. NOVAK, OF ST. PAUL, MINNESOTA.

BAG.

Application filed December 27, 1926. Serial No. 157,140.

The present invention relates to a shopping bag and more particularly to a shopping bag having a carrying cord extending around the bottom thereof and anchored 5 thereto through openings in the bottom of said bag.

An object of the present invention is to make a shopping bag having a pair of carrying handles therefor extending downwardly through perforations in the sides thereof and around the bottom of said bag to provide a simple handle construction which will give a maximum degree of support for the contents of said bag, the carrying handles 15 being anchored to each other and to the bag through holes in the bottom of said bag.

In order to attain this object, there is provided, in accordance with one feature of the invention, a paper bag having a folded bottom portion and having a pair of carrying cords passed through perforations in opposite sides of the bag and brought up through perforations in the bottom of the bag, being tied together on the interior of the bag bottom to anchor the cord against slippage.

These and other features of the invention will be more fully brought out in the following description and the accompanying drawings, wherein:

Figure 1 is a view in perspective of an ordinary type of large paper bag having a pair of carrying handles constructed in accordance with the present invention.

Figure 2 is a view in lower elevation of the bag shown in Figure 1.

Figure 3 is a view in perspective of a modified form of bag having the handles thereof constructed in accordance with the present invention.

Figure 4 is a fragmentary sectional view on the line 4—4 of Figure 2; and

Figure 5 is a view in perspective of the carrying cords alone as they would appear when mounted on a bag.

Referring to the drawings in detail, a bag A is perforated on each side near the upper edge thereof as at 1 and 2, and also at 3 and 4, just below the lateral crease 5, at which point the bottom 6 of the bag may be folded 50 parallel with either side of the bag in a well known manner. The bottom of the bag is perforated at 7 and 8 on each side, said perforations being in line with the perforations 3 and 4 in the side of the bag, and 1 and 2

near the upper edge thereof. Since the position of the openings for receiving the carrying cords, and the carrying cords themselves are duplicated on opposite sides of the bag, reference will be had to the structure of but one side of the bag. The perforations in the bottom of the bag are preferably made through the maximum number of thicknesses of the bag material which occur on the bottom of the bag. One familiar with bag construction is aware of the fact that the bottoms of both types of bags shown are folded in the manner shown in Figure 2, where two end flaps 9 and 10, shown in dotted lines, are folded, and two side flaps 11 and 12 are then folded across to overlap one another, as illustrated. Three thicknesses of the bag material are thus provided at the points where the perforations 7 and 8 are made in the bottom of the bag. After perforating the bag in the manner illustrated and described, a pair of carrying cords 13 and 14 are inserted, one for each side of the bag, each cord being looped at its center and one side thereof passed in through the top openings 1 and 2, thence downwardly along the inside of the bag wall outwardly through the lower openings 3 and 4 and upwardly through the bottom openings 7 and 8. The ends of the cords 13 and 14 are drawn up a short distance inside of the bag 85 to give them sufficient length to permit of their being knotted together as at 15 (Figures 4 and 5). After knotting, the handles 13 and 14 are drawn taut to force the knots 15 down against the inner surface of the 90 bottom of the bag. The knot firmly locks the cord against slippage and the passing of the cord through the openings in the bottom of the bag also firmly locks the cord against slipping outwardly over the ends of the bag. 95 Since the perforations in the bottom of the bag are through several thicknesses of bag material, the carrying cords are anchored at points of maximum strength of the bag, which makes the point of anchorage one of 100 the strong points of the bag. It also gives carrying support to the lower edges of the bag which is lacking in constructions where the cord passes through openings adjacent said lower edge to pass inside of said edge. 105

A modified form of bag B is shown in Figure 3. This bag, of the type commonly referred to as satchel bottom bag, has the

sides thereof folded inwardly as at 16. The carrying cords and perforations in this modified form of bag all find their substantial equivalent in the construction shown in Figures 1 and 2. It will suffice, therefore, to number the parts of this bag in the same sequence as the parts of the bag A, the parts of the bag B, however, being primed to distinguish from the identifying numerals of the bag A. The bag B illustrated in Figure 3, is intended to be made of heavier material than the bag A, such as a heavier grade of paper, or leatherette, to provide a carrier in the nature of a small valise or hand bag. Since the sides of this bag fold inwardly instead of outwardly, a bag of this type, having the same over all width when folded as the type of bag shown in Figure 1, would have a much larger carrying capacity.

By running the carrying cords 13 and 14 below the creases or folds 5 before bringing them out through the openings 3 and 4, these creases or folds are forced outwardly upon opening the bag and drawing the handles taut, which assists the bag in assuming its proper shape under a load and precludes the possibility of carrying the bag with the bottom folded against one side or the other, as frequently happens when carrying cord handles are employed passing around the bottom of a bag and entering the sides thereof above this line of fold.

I claim:

35 1. A shopping bag having a pair of perforations in each side thereof near the top of the bag, a second pair of perforations in

the side wall of the bag below the lateral crease at which the bottom of the bag falls against the side wall of the bag, and two pairs of perforations at the bottom of said bag, each pair of said perforations being in vertical alignment with the top and lower side openings in one side of the bag, and a pair of carrying cords, each of which is looped in the center and the ends of which are passed inwardly through the top openings, in the side wall of the bag, thence downwardly along the interior of the bag, outwardly through the openings in the lower side wall of the bag, around the lower edge of the bag, and thence upwardly through one of each pair of openings in the bottom of the bag, the ends of opposite carrying cords being knotted together to secure them together and to hold the carrying cords against slippage.

2. A shopping bag comprising a collapsible bag having two pairs of perforations in the bottom thereof, the perforations of each of said pairs being closely adjacent each other, a pair of cords looped above the upper edge of said bag upon either side thereof to form handles and passing downwardly around the lower edge of said bag and upwardly through one of each of said pairs of openings in the bottom of said bag, the ends of said cords in each of said pairs of openings being knotted together with a knot larger than said perforations in the bottom of said bag to anchor the cords against slippage.

In testimony whereof I affix my signature.

ROBERT C. GROH.
